UNITED STATES PATENT OFFICE.

HALFDAN A. STEEN, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

SWITCH.

1,279,778.

Specification of Letters Patent. Patented Sept. 24, 1918.

Application filed June 19, 1911. Serial No. 634,149.

To all whom it may concern:

Be it known that I, HALFDAN A. STEEN, a subject of the King of Norway, residing at Milwaukee, in the county of Milwaukee, and State of Wisconsin, have invented certain new and useful Improvements in Switches, of which the following is a full, clear, and exact specification.

My invention relates to the construction of switches or circuit-breakers.

It is the object of my invention to improve the operating mechanism and the contact arrangement of such devices. A movable switch arm is pivoted to a support, and an operating arm is pivoted to the switch arm and in its movement bears on a fixed guide to produce the desired movement of the switch arm. The switch arm carries main and arcng contacts, which coöperate respectively with other main and arcng contacts. Of a pair of coöperating main contacts, one is mounted on a pivoted lever which is tilted by the closing movement of the switch arm to move the main contact on the pivoted lever transversely to the movement of and into engagement with the other main contact. One of the main contacts comprises a group of laminae clamped between an abutment and a pivoted clamping lever. Of a pair of coöperating arcng contacts, one is yieldable relatively to the corresponding main contact and its mounting.

The various novel features of my invention will appear from the description and drawings, and will be particularly pointed out in the claims.

Figures 1 and 2 show the closed and open positions respectively of a circuit-breaker embodying my invention.

On a base 10, of suitable insulating material, are mounted a pair of main supporting plates 11, between which extends a pivot pin 12 carrying a main switch arm 13. This arm carries a main contact 14, a metal auxiliary contact 15, and a carbon arcng contact 16. The main contact comprises a group of metal laminae, the contact moving in a plane parallel to the plane of the paper. These laminae 14, together with the spring support 17 for the auxiliary contact 15 and the end of a flexible conductor 18, are clamped between an abutment 19 and a lever 20 pivoted at 21. The requisite clamping pressure is obtained by means of a screw 22. The flexible connection 18 leads to one terminal of the

overload coil 23, the other terminal of which is connected to the bolt 24 which is provided for making one of the switch connections. The other switch connection is made by a bolt 25 extending from the support 26 for contacts 27, 28, and 29 which coöperate with the contacts 14, 15 and 16. The contacts 27, 28, and 29 are mounted on a pivoted lever 30, the first two being fixed with relation to such lever, and the last being attached thereto by a leaf spring 31. The lever 30 is biased to the position shown in Fig. 2, as by means of a spring 32, but upon the closing of the switch is moved to the other position by an adjustable roller 33 carried by the switch arm 13. Such closing movement is attained by an operating arm 34, which is pivoted to the arm 13 and provided with a handle 35. On the sides of the arm 34 are mounted rollers 36 which run on guides 37 formed on extensions of the supports 11.

When the switch is open the parts are as shown in Fig. 2. By pressing down the handle 35, the operating arm 34 is turned about its pivot on the arm 13 and pressure is exerted between the rollers 36 and the guides 37. The guide 37 being fixed, the reaction on the switch arm 13 forces said arm from the open position shown in Fig. 2 to the closed position shown in Fig. 1. As the arm 13 approaches its closed position, the carbon arcng contacts 16 and 29 first engage, then the roller 33 strikes the upper end of the lever 30 and turns such lever in a counter-clockwise direction to bring the main contact 27 into engagement with the free ends of the laminae of the main contact 14. The auxiliary contacts 15 and 28 engage after the arcng contacts but before the main contacts engage. Because of the spring mounting of the contacts 15 and 29, a firm engagement between the contacts on each pair of contacts is obtained. When the switch arm 13 reaches its full closed position, a latch 38, pivoted at 39, engages a projection 40 on the operating arm 34, thus holding the switch in closed position.

Upon an overload, the overload coil 23 attracts its armature 41, and a projection 42 upon the latter engages an upwardly extending arm 43 on the latch 38 and tilts such latch to disengage it from the projection 40. In case of a failure in the voltage on the line, the no-voltage coil 44 releases its armature 45, which is immediately tilted in a

counter-clockwise direction by its spring 46, so that a roller 47 carried by an arm projecting from such armature strikes the roller 48 fastened to a projection 49 from the latch 53 and causes the disengagement of said latch from the projection 40. Upon such disengagement, whether because of overload or no-voltage, the springs 31 and 32 force the switch arm 13 in a clockwise direction to the 10 position shewn in Fig. 2, and the spring 32 tilts the lever 30 in the same direction. This opens the switch, the main contacts separating first, the auxiliary contacts next, and the arcing contacts last. When the switch arm 15 reaches open position, any shock is taken by the buffer 50.

There may be many modifications in the precise arrangement shown and described, and I aim to cover all such modifications 20 which do not involve a departure from the spirit and scope of the invention as set forth in the appended claims.

What I claim as new is:

1. In a switch, the combination of a base, 25 a switch mounted on said base and comprising a pivoted switch arm, an operating arm pivoted thereto, and a fixed guide on which said operating arm bears, said guide extending transversely of the plane of the adjacent face of said base.
2. In a switch, the combination of a base, 30

a switch mounted on said base and comprising a movable contact-carrying element, an actuating arm pivoted to said movable element, and a fixed guide on which a portion 35 of said actuating arm bears, said guide extending transversely of the plane of the adjacent face of said base.

3. In a switch, the combination of a pivoted switch arm, an actuating arm pivoted thereto, a fixed member provided with a guiding portion on which a portion of said actuating arm bears, a latch mounted on said member and operative to hold said actuating arm in a position corresponding to closed 45 position of the switch, and a plurality of separate means comprising an actuating element pivotally mounted on said member for releasing said latch.

4. A switch contact comprising a group 50 of laminae, an abutment and a pivoted lever between which said laminae are located, and means for forcibly swinging said lever to clamp the laminae between it and the abutment.

Milwaukee, Wis., June 16, 1911.

In testimony whereof I affix my signature, in the presence of two witnesses.

HALFDAN A. STEEN.
